(57) **CLAIM**

We claim the ornamental design for a hand tool handle, as shown and described.

DESCRIPTION

FIG. 1 is a perspective view of a hand tool handle according to my new design;

FIG. 2 is a front elevational view of the hand tool handle of FIG. 1;

FIG. 3 is a rear elevational view of the hand tool handle of FIG. 1;

FIG. 4 is a right side elevational view of the hand tool handle of FIG. 1;

FIG. 5 is a left side elevational view of the hand tool handle of FIG. 1;

FIG. 6 is a top plan view of the hand tool handle of FIG. 1; FIG. 7 is a bottom plan view of the hand tool handle of FIG. 1; and,

FIG. 8 is an alternate perspective view of the hand tool handle of FIG. 1, the broken lines of the hand tool handle are for illustrative purposes only and form no part of the claimed design.
